(57) **CLAIM**

The ornamental design for a chalk marker and dispenser, as shown and described.

DESCRIPTION

FIG. 1 is an exploded view of a chalk marker and dispenser showing my new design;

FIG. 2 is a perspective view thereof;

FIG. 3 is a perspective view of the lower part of the barrel shown without the upper part of the barrel or the cap for convenience;

FIG. 4 is a front view thereof; the rear view being a mirror image thereof;

FIG. 5 is a top plan view thereof; the bottom plan view being a mirror image thereof;

FIG. 6 is a left side view thereof;

FIG. 7 is a rear view of the cap shown without the barrel for convenience;

FIG. 8 is a front perspective view thereof;

FIG. 9 is a bottom plan view thereof; the top plan view being a mirror image thereof; and,

FIG. 10 is a right side view thereof.

1 Claim, 3 Drawing Sheets
